UNITED STATES PATENT OFFICE.

CARL WINKLER, OF BERNE, SWITZERLAND.

DEVICE FOR DRIVING THE IMPRESSION-CYLINDERS OF PRINTING-MACHINES.

1,252,069.

Specification of Letters Patent.

Patented Jan. 1, 1918.

Application filed April 25, 1916. Serial No. 93,507.

To all whom it may concern:

Be it known that I, CARL WINKLER, a citizen of the Swiss Republic, residing at Berne, in the Swiss Republic, have invented a new and useful Improved Device for Driving the Impression-Cylinders of Printing-Machines, of which the following is a specification.

My invention relates to a device to be used on printing machines for enabling the toothed parts connecting the form and impression cylinder to be kept in engagement with each other even when the impression cylinder has been moved radially away from the form.

15 On the accompanying drawing one construction of the device is shown by way of example in connection with a printing machine having a reciprocating type-carriage and an oscillating cylinder.

20 Figure 1 is an end view of the impression cylinder together with its bearing and a part of the frame of the machine,

Fig. 2 shows a vertical section of the parts. Both ends of the shaft *a* of the impression cylinder *b* are journaled in an eccentrically bored sleeve *c*, which is adapted to be turned through a certain angle by the arm *d* and rod *e* from any suitable point of the machine. In the end position of the arms *d* and sleeves *c* shown in both figures of the drawing the impression cylinder *b* will bear against the form passing underneath it, while if said arm *d* is pulled down by the rod *e* the sleeve *c* will be turned, and by 35 changing its position will raise the shaft *a* and cylinder *b*. As a consequence this cylinder will not bear against the form during its return stroke.

40 *f* is the spur-wheel by which the impression cylinder *b* is driven. This spur-wheel engages in the toothed rack *g* which is reciprocated backward and forward with the form, and, according to my invention, these parts *f* and *g* are to be kept in engagement not only during the forward motion of the form, but also when the form returns and the impression cylinder *b* is raised.

With this object in view the spur-wheel *f* is not fastened on the shaft *a*, but turns loosely on the hub *h*, cast in one piece with the frame *i* of the machine, and it is connected with the impression cylinder *b* by a pin *k* passing through a block *l* adapted to slide in the groove *m* in said gear. This sliding connection enables the cylinder to be raised and lowered in regard to the spur-wheel *f* without the driving relation of these parts being interfered with, so that the impression cylinder, in both the raised and lowered position, continues to be oscillated 55 backward and forward by the reciprocating rack *g*.

What I claim and desire to secure by Letters Patent of the United States is:

A printing machine comprising in combination an impression cylinder, eccentrically bored sleeves in which said cylinder is journaled, frames carrying said sleeves, means to turn said sleeves in said frame to raise and lower said impression cylinder, a hub on one 65 of said frames directed toward said cylinder, a spur-wheel supported on said hub close against the end of said cylinder and concentric to said impression cylinder during the printing period, a toothed element 70 adapted to rotate said spur-wheel and always remaining in engagement with said spur-wheel, and a radially sliding connection between said spur-wheel and cylinder adapted to transfer the rotary motion of 75 said spur-wheel to said cylinder and to simultaneously permit said spur-wheel and cylinder to turn about axes eccentric to each other, substantially as, and for the purpose, 80 set forth.

85 In testimony whereof I have signed my name to this specification in the presence of two subscribing witnesses.

CARL WINKLER.

Witnesses:

MAX BAEHR,
H. J. STEHLIN.
